United States Patent Office

Des. 192,375
Patented Mar. 13, 1962

192,375

BOWL

Clayton A. Laughlin, Minneapolis, Minn., assignor to Arthur Salm Inc., Chicago, Ill., a corporation of Illinois

Filed Sept. 5, 1961, Ser. No. 66,609

Term of patent 14 years

Claims priority, application Germany Mar. 7, 1961

(Cl. D44—15)

I claim:

The ornamental design for a bowl, substantially as shown.
